UNITED STATES PATENT OFFICE.

ALBERT E. PALMER, OF OWOSSO, MICHIGAN, ASSIGNOR OF ONE-HALF TO
ALFRED T. THOMAS, OF SAME PLACE.

CLAMPING DEVICE FOR GLUE-PRESSES.

SPECIFICATION forming part of Letters Patent No. 625,193, dated May 16, 1899.

Application filed March 13, 1899. Serial No. 708,918. (No model.)

To all whom it may concern:

Be it known that I, ALBERT E. PALMER, a citizen of the United States, residing at Owosso, in the county of Shiawassee and State 5 of Michigan, have invented certain new and useful Improvements in Clamping Devices for Glue-Presses; and I do hereby declare that the following is a full, clear, and exact description of the same, reference being had to 10 the annexed drawings, making a part of this specification, and to the letters of reference marked thereon.

The present invention has reference to that 15 class of devices which are employed for securely holding glued boards together at their edges to secure a perfectly tight joint and is designed as an improvement upon my former patent, dated April 11, 1893, No. 495,054, wherein are employed notched clamping-bars 20 and levers for forcing the sections composing the stock closely together.

The invention consists in a glue press or device constructed substantially as shown in the drawings and hereinafter described and 25 claimed.

Figure 1 of the drawings is a plan view of 30 the device, showing the two boards in position in dotted lines; Fig. 2, a longitudinal vertical section on line 2 2 of Fig. 1, also showing a second device below it to illustrate the relative positions thereof when in use; and Fig. 3, a horizontal section on line 3 3 of Fig. 2 and on an enlarged scale.

In the accompanying drawings, A represents the notched clamping-bar, which may 35 be of any desirable width and length and of any preferred construction. This clamping-bar has a suitable opening a, and to the bar over said opening is connected the horizontal 40 plate B by means of the blocks b, so as to retain said plate the desired distance above the bar. The plate B upon its upper side is cast or otherwise provided with a tooth C, adapted to enter and engage the opening a of the 45 clamping-arm located directly above it, as illustrated in Fig. 2 of the drawings.

The outer end of the clamping-bar A has 50 pivotally connected thereto an operating hand-lever D, provided with ratchet-teeth c, with which engages the spring-actuated pawl

d, pivotally connected to the clamping-bar, thereby holding the lever against turning back when being operated. Any suitable spring-pawl may be substituted for that shown, and in the present instance I have provided the 55 pawl with a thumb-piece e for releasing the pawl from engagement with the ratchet-teeth. The enlarged end of the lever is disposed between the ends of the clamping-bar A and the horizontal plate B, the pivotal pin f serving 60 to connect the bar and plate together.

To the enlarged end of the lever D is eccentrically pivoted one end of a link E, and the opposite end of the link is pivoted to a movable clamping-jaw F of any preferred 65 construction. In the present instance I have shown the clamping-jaw F provided with a slotted shank G to enable the shank to slide on the clamping-bar without interfering with the blocks b and also providing said shank 70 with guide-flanges g, which extend above and below the shank and against the edges of the stationary plate B and the clamping-bar A, thereby preventing the shank from lateral movement while moving lengthwise of the 75 clamping-bar A.

The enlarged end of the hand operating-lever D may have a curved bearing h for the curved end of the eccentrically-operating link E to take the strain off the pivotal pin of said 80 link.

In using the glue press or device a suitable frame or support, as shown in my former patent, may be employed or any other preferred 85 construction of frame or platform for supporting the lower one of the devices, the notched ends of the clamping-bars engaging with a slotted standard H, as shown in Fig. 1 of the drawings. In Fig. 2 of the drawings is shown in dotted lines the position of the 90 platform or support and the boards between the slotted standard and the clamping-jaws. As this frame or support may be variously modified or one of any suitable construction may be used, it is not deemed necessary to 95 show in detail its construction, and therefore the position of the frame or platform relative to the clamping devices (indicated in dotted lines) is believed to be sufficient. It will be seen that as each clamping device is provided 100

with a socket or opening and a holding-tooth C the several devices may be locked into each other to prevent springing and drawing of the devices, this being considered an essential feature of the invention, as it locks together the entire number of the clamping devices used and holds them in line and against lateral displacement. The boards being placed upon the clamping-bar A and between 5 the clamping-jaw F and the slotted standard H of the frame or support, by operating the lever D the clamping-jaw will be forced against the boards to securely hold them together while the glue is drying. The eccentrically-pivoted link E provides a most perfect means of forcing the clamping-jaw forward, and the spring-actuated pawl d, which engages with the ratchet-teeth c of the hand-lever, holds the clamping-jaw in position 10 against the board and prevents it from receding. In the general construction of this clamping device there are many changes or modifications in the several details that may be made without departing from the principle 15 of the invention, as in the clamping-bar and the clamping-jaw, the spring-actuated pawl, and the operating hand-lever, all of which may be modified or changed in form and construction without affecting their operation.

20 Having now fully described my invention, what I claim as new, and desire to secure by Letters Patent, is—

25 1. A clamping device for glue-presses, consisting of a clamping-bar adapted to be coupled to and co-operating with a part of said press forming one clamp-face therefor, said bar provided with a holding-tooth on one lateral face and an opposite socket or opening so arranged that the tooth and socket of adjacent bars will interlock to maintain a series of 30 the bars in alinement, and a movable clamp-

ing-jaw and lever for operating it, substantially as and for the purpose set forth.

2. A clamping device for glue-presses, consisting of a clamping-bar adapted to co-operate with others and with a base forming one clamping-jaw and having respectively a counterpart holding-tooth and a socket on opposite sides so that a series of said bars may be interengaged to maintain the series in line, and 45 a movable clamping-jaw on said bar, an operating-lever with ratchet and a pawl adapted to engage the teeth on the ratchet, and an eccentrically-pivoted link connecting the movable clamping-jaw with the lever, substantially 50 as and for the purpose described.

3. A clamping device for glue-presses, consisting of a clamping-bar having a series of notches near one end to engage a slotted standard, and a movable clamping-jaw, a lever operating it and having a curved bearing-rib, an eccentrically-pivoted link connecting the lever with the clamping-jaw and resting against the curved rib which transmits the clamping strain, substantially as and for the 55 purpose specified.

4. A clamping device for glue-presses, consisting of a clamping-bar, an operating-lever having a lateral curved bearing-rib, a movable clamping-jaw, an eccentrically-pivoted link 60 connecting said lever with the jaw, ratchet-teeth upon the inner end of the lever, and a spring-actuated pawl adapted to engage with the teeth, substantially as and for the purpose 65 set forth.

In testimony that I claim the above I have hereunto subscribed my name in the presence of two witnesses.

ALBERT E. PALMER.
